UNITED STATES PATENT OFFICE.

FRANCIS H. WHITMAN, OF CAMBRIDGE, MASSACHUSETTS.

POLARIZED RINGER-MAGNET.

No. 866,760.

Specification of Letters Patent.

Patented Sept. 24, 1907.

Application filed December 31, 1906. Serial No. 350,120.

To all whom it may concern:

Be it known that I, FRANCIS H. WHITMAN, a citizen of the United States, residing at Cambridge, in the county of Middlesex and State of Massachusetts, have 5 invented a certain new and useful Improvement in Polarized Ringer-Magnets, of which the following is a specification, reference being had therein to the accompanying drawings.

One object of the invention is to provide a simple 10 and effective means for securing the electro magnets in fixed relation to each other.

Another object of the invention is to provide for the armature a yoke support which is fixedly held by the cores of the electro magnets and to provide simple 15 mechanism for adjusting the distance between the armature and the poles or cores of the electro magnets.

Another object of the invention is to provide means by which the electro magnets are held in fixed relation with each other in such manner as to permit the easy 20 removal of either one of the electro magnets and the substitution of another one therefor without disturbing the remaining electro magnet.

Another object is to attach the permanent magnet in such manner that it may be detached without disturbing 25 the adjustment of the other parts.

The invention will be fully understood from the following description taken in connection with the accompanying drawings, and the novel features thereof are pointed out and clearly defined in the claims at 30 the close of the specification.

In the drawings,—Figure 1 is a front elevation of a polarized ringer magnet embodying the invention. Fig. 2 is a vertical section on line 2—2 of Fig. 1 enlarged. Fig. 3 is an enlarged front elevation partly in 35 section, the bells and supporting table therefor being removed and the windings of the electro magnets being diagrammatically shown so as to more clearly show the cores. Fig. 4 is a section on line 4—4 of Fig. 3. Fig. 5 is an enlarged detail of the grooved nut which 40 binds the bridge to the stem of the yoke. Fig. 6 is an enlarged detail plan of the bifurcated spring washer which straddles the neck of the grooved nut to frictionally engage the bridge. Fig. 7 is a cross-section on line 7—7 of Fig. 6. Fig. 8 is a sectional detail of the 45 core of one of the electro magnets, showing also the yoke and armature.

Referring to the drawings,—the apparatus shown in the drawings as embodying the invention contains two electro magnets 1, 1, each provided with a core 2 which 50 is secured to a connecting strap 3 as will be described, this strap 3 serving as a bracket by which the apparatus is attached to a suitable table or support 4 which may be the side of the box or other suitable support on which are mounted the bells 5.

55 A permanent magnet 6 is secured at one end to the strap 3 by a screw 33 and extends alongside the electro

magnets at some greater length than the electro magnets, and at its other end it is turned so as to extend beneath the armature and its support.

The electro magnets 1 are secured to the strap 3 by 60 screws 7 which pass through holes in the strap and are screwed into the tapped out ends of the cores 2. The other ends of the cores 2 extend beyond the heads of the spools 8 and the projecting end of each is formed with a transverse groove 9, forming a flange head 10. 65 A yoke 11 is formed with a slot 12 at each end thereof wide enough to receive the necks formed by the grooves 9 of the cores, these slots forming bifurcated ends of the yoke which straddle the necks of the cores formed by the grooves, the yoke being thick enough to fit snugly 70 within the grooves. The longitudinal distance from the inner end of one slot 12 to the inner end of the other slot 12, as indicated by the dotted line 15, is enough to prevent the two electro magnets from being drawn up quite parallel with each other when the screws 7 75 are set up. The electro magnets are secured to the strap 3 by screws 7 passing through the strap 3 and extending axially into the ends of the cores 2. When these screws 7 are set up, the tendency is to draw the electro magnets into a perpendicular position with 80 relation to the face of the strap 3, and thus into parallel relation with each other. Before the screws are fully set up, however, the yoke 11 is placed in position at the opposite ends of the electro magnets with the slotted ends 12 engaging the grooves of the cores, the magnets 85 slightly diverging from each other toward the ends engaged by the yoke 11 by reason of the distance between the slots being as already stated sufficient to prevent the cores from being brought parallel with each other. As the screws are set up, drawing the cores of the electro magnets more nearly into parallel relation with each other, the grooved necks of the cores will be caused to grip the slotted ends 12 of the yoke more and more firmly, thereby binding the yoke and the electro magnets firmly together. 95

The lines 31—31 in Fig. 3 are drawn through the axes of the cores, and show the divergence of the cores. The lines 32—32 are parallel with each other and indicate the position that the axes of the cores would occupy 100 if the cores did not diverge.

Projecting from the outer face of the yoke 11, preferably midway thereof at a point in a line joining the axes of the two cores of the magnets, is a post or stud 16 which passes freely through a hole 17 in the armature 18 and is threaded to receive a flanged tapped out sleeve or adjusting nut 19 having a tubular neck 190 which passes through a hole in the bridge 20. The bridge 20 is formed with upturned ends forming arms 201, and the yoke 11 is formed with laterally extending arms 21, 22, each of which is slotted at the end to receive the upturned arms 201 of the bridge, said slots being of proper size and location for the said upturned arms 201 to fit closely 110

therein. Projecting inward from the upturned arms 201 are the pivot bearings 23 on which the armature 18 is pivoted. The neck 190 is formed with an annular groove 191 which is straddled by a forked friction 5 washer which as shown is a cupped out spring clip 24. This spring clip 24 presses against the inner face of the bridge 20 and clamps the said bridge against the flange head of the nut 19. The bridge is thus held securely in position by reason of the body of the bridge being 10 clamped between the head of the screw 19 and the spring clip 24 and the upturned arms 201 engaging in the guide slots 210 and 220 in the arms 21 and 22 of the yoke 11. By turning the nut 19, the bridge 20 will be moved toward or from the yoke 11, thereby limiting 15 the vibratory movement of the oscillating armature.

Secured to the armature 18 is a lever 25 which extends up through a slot 26 in the yoke 11 and through a slot 27 in the permanent magnet 3, also through the table 4, carrying at its upper end a bell tapper 28 which, 20 as the armature vibrates, alternately taps the bell 5.

The bridge 20 being clamped between the flange head of the nut 19 and the spring clip 24, and the arms 201 being engaged in the guide slots 210 and 220 of the yoke 11, the said yoke and bridge are bound together in 25 whatever position they are adjusted relative to each other. By means of the screws 7 and the slotted yoke 11, the two electro magnets are clamped firmly in position independently of each other, so that if it be desired at any time to remove either one of the electro magnets 30 to replace it by another, or for any other purpose, either one of said electro magnets may be easily removed by simply removing the table 4 from the strap 3 and then withdrawing either one of the screws 7 according to whichever electro magnet it is desired to replace, and 35 then such electro magnet may easily be slipped out without disturbing the other one. It is also apparent that by turning the nut 19 the distance between the armature and the cores 9 of the electro magnets may be varied and adjusted according to the extent of vibration 40 desired.

The permanent magnet 6 is, as already described, secured directly to the strap 3, and this connection is independent of the means by which the electro magnets are secured to said strap by screws 7 and the permanent 45 magnet is also entirely free from any connection with the yoke 11 and bridge 20 which support the other ends of the electro magnets. Thus the permanent magnet may be easily removed and replaced by another without interfering in any way with the adjustment of the 50 ringer.

I claim as my invention:

1. In a polarized ringer magnet, two electro magnets, each electro magnet having a core which at one end extends beyond the end of the said magnet, said extending ends being each formed with a transverse groove, a yoke having slotted ends which embrace the necks of said cores formed by said grooves, a strap to which said electro magnets are attached at their other ends by means of screws which are screwed axially into the ends of said cores, the distance 55 between the inner ends of the slots formed in said yoke being sufficient so that when said members are assembled, the slotted yoke will hold the cores in divergent relation to each other in the direction of the grooved ends, and by setting up said screws, the said slotted yoke will be 60 clamped between said grooved cores.

2. In a polarized ringer magnet, two electro magnets, a support therefor to which said magnets are secured at one end, means for securing said magnets to the said support

tending to draw them into parallel relation to each other, each electro magnet having a core which at the opposite 70 end from said support extends beyond the end of the said magnet, said extending ends being each formed with a transverse groove, a yoke having slotted ends which embrace the grooved necks of said cores and hold them in a slightly divergent relation to each other, said slotted ends 75 being brought into clamping engagement with said grooved necks when the securing means for the opposite ends are set up.

3. In a polarized ringer magnet, two electric magnets, a support therefor to which said magnets are secured at one 80 end, means for securing said magnets to the said support tending to draw them into parallel relation to each other, each electro magnet having a core which at the opposite end from said support extends beyond the end of the said magnet, said extending ends being each formed with a 85 transverse groove, a yoke having slotted ends which embrace the grooved necks of said cores and are spaced apart to hold them in a slightly divergent relation to each other when fully assembled, said slotted ends being brought into clamping engagement with said grooved necks of the cores 90 when the securing means for the opposite ends are set up, a stud projecting outward from said slotted yoke in a line parallel with the cores of said magnets, a bridge secured to said slotted yoke by a flanged tubular sleeve passing through said bridge and screwed onto said stud and a friction washer which clamps said bridge against the head of 95 said flanged sleeve.

4. In a polarized ringer magnet, two electro magnets, a support therefor to which said magnets are secured at one 100 end, means for securing said magnets to said support tending to draw them into parallel relation to each other, each electro magnet having a core which at the opposite end from said support extends beyond the end of the said magnet, said extending ends being each formed with a transverse groove, a yoke having slotted ends which embrace the grooved necks of said cores and are spaced apart to hold them in a slightly divergent relation to each other when fully assembled, said slotted ends being brought into clamping engagement with said grooved necks of the cores 105 when the securing means for the opposite ends are set up, a stud projecting outward from said slotted yoke in a line parallel with the cores of said magnets, a bridge secured to said yoke by a flanged tubular sleeve passing through said bridge and screwed onto said stud, means for clamping said bridge against the flanged head of said sleeve, 110 whereby said bridge may be held at a fixed distance from said yoke and a vibrating armature pivoted to said bridge.

5. In a polarized ringer magnet, two electro magnets, a support therefor to which said magnets are secured at one 115 end, means for securing said magnets to said support tending to draw them into parallel relation to each other, each electro magnet having a core which at the opposite end from said support extends beyond the end of the said magnet, said extending ends being each formed with a transverse groove, a yoke having slotted ends which embrace the 120 grooved necks of said cores and are spaced apart to hold them in a slightly divergent relation to each other when fully assembled, said slotted ends being brought into clamping engagement with said grooved necks of the cores when the securing means for the opposite ends are set up, a stud projecting outward from said slotted yoke in a line parallel with the cores of said magnets, guide slots in the sides of said yoke, a bridge having arms which engage said guide slots in said yoke, a flanged tubular sleeve which passes through said bridge and screws onto the stud which projects from said yoke, means for clamping said bridge against the flanged head of said tubular sleeve, the said 125 tubular sleeve being adjustable on said stud whereby said bridge may be adjusted toward and from said yoke, said guide slots and clamping means holding said bridge firmly in its adjusted position, a vibrating armature between said yoke and said bridge and pivot bearings in said arms of the bridge for said armature.

6. In a polarized ringer magnet, two electro magnets, a strap to which said electro magnets are secured at one end 130 by screws passing through said yoke and extending axially into the ends of the cores of said electro magnets, the other ends of said cores extending beyond the heads of said

- magnets, said extending ends being each formed with a transverse groove, a yoke having slotted ends which embrace the grooved necks of said cores and hold them in a slightly divergent relation to each other when said screws 5 are set up, said slotted ends being brought into clamping engagement with the said grooved necks when said screws are set up in the opposite end. 7. In a polarized ringer magnet, two electro magnets, a strap to which said electro magnets are secured at one end 10 by screws passing through said strap and extending axially into the ends of the cores of said electro magnets, the other ends of said cores extending beyond the heads of said magnets, said extending ends being each formed with a transverse groove, a yoke having slotted ends which 15 embrace the grooved necks of said cores and hold them in a slightly divergent relation to each other when said screws are set up, said slotted ends being brought into clamping engagement with the said grooved necks when said screws are set up in the opposite end, a screw threaded stud projecting outward from said slotted yoke in a line parallel 20 with the cores of said magnets, a bridge secured to said slotted yoke by means of a tapped out flanged sleeve passing through said bridge and screwed onto said stud, means for clamping said bridge against the flanged head of said 25 sleeve, and a vibrating armature pivoted to said bridge between the bridge and said slotted yoke. 8. In a polarized ringer magnet, two electro magnets, a strap to which said magnets are secured at one end, means for securing said magnets to the said strap tending to 30 draw them into parallel relation to each other, each electro magnet having a core which at the opposite end from said strap extends beyond the head of the said magnet, said extending ends being each formed with a transverse groove, a yoke having slotted ends which embrace the 35 grooved necks of said cores and hold them in a slightly divergent relation to each other, said slotted ends being brought into clamping engagement with said grooved necks when the securing means for the opposite ends are set up and a permanent magnet secured to said strap by means 40 independent of the means which secure said electro magnets to said strap. 9. In a polarized ringer magnet, two electro magnets having cores which at one end extend beyond the heads of said magnets, said extending ends being formed with transverse grooves, a yoke having slotted ends which engage 45 said grooved extensions of the cores, a bridge having upturned arms which engage with slots in the sides of said yoke, a screw threaded stud which projects outwardly from said slotted yoke intermediate its ends, a nut having 50 a tubular tapped out neck which passes through a hole in said bridge and screws onto said screw threaded stud, means for clamping said bridge against the head of said nut, said bridge being adjustable toward and from said slotted yoke by means of said nut and being held in its 55 adjusted position with relation to said yoke by said nut and clamping means and the engagement of the arms of the bridge with said slotted yoke, and a vibrating armature pivoted between said yoke and the bridge by pivots journaled in the arms of said bridge. 60 10. In a polarized ringer magnet, a vibrating armature, an adjustable support for said armature comprising a yoke having slotted ends which engage the cores of said electro magnets, a bridge having arms which engage with guide slots in the sides of said yoke, a screw threaded stud projecting outwardly from said yoke parallel with the axis of 65 said electro magnets, and a nut having a tubular neck which passes through said bridge and screws onto said threaded stud which projects from said yoke. 11. In a polarized ringer magnet, two electro magnets, each having a core which projects at one end thereof, said projecting ends being formed with transverse grooves, a yoke having slotted ends which engage the grooves in said cores, a bridge, a vibrating armature pivoted to said bridge, means for securing said bridge to said slotted yoke in 70 adjustable relation thereto, whereby said armature may be adjusted at varying distances from the cores of said electro magnets. 12. In a polarized ringer magnet, two electro magnets each having a core which projects at one end thereof, said projecting ends being formed with transverse grooves, a yoke having slotted ends which engage the grooves in said cores, a bridge having arms which engage with guide slots in the sides of said yoke, a screw threaded stud which projects outwardly from said yoke parallel with the axis of said electro magnets, a flanged sleeve which passes through said bridge and is tapped out to screw onto the said stud, a transverse groove in said sleeve, a friction washer which straddles the neck of said groove and clamps said bridge against the flanged end of said sleeve and a vibrating armature pivoted to the arms of said bridge, said bridge being adjustable toward and from said yoke by means of said sleeve. 13. In a polarized ringer magnet, two electro magnets each having a core which projects at one end thereof, said projecting ends being formed with transverse grooves, a yoke having slotted ends which engage the grooves in said cores, a bridge having arms which engage with guide slots in the sides of said yoke, a screw threaded stud which projects outwardly from said yoke parallel with the axis of said electro magnets, a flanged sleeve which passes through said bridge and is tapped out to screw onto the said stud, a transverse groove in said sleeve, a spring clip which straddles the neck of said groove and clamps said bridge against the flanged end of said sleeve and a vibrating armature pivoted to the arms of said bridge, said bridge being adjustable toward and from said slotted yoke by means of said sleeve, and a strap to which the other ends of said electro magnets are secured by means of screws which pass through said strap and extend axially into the ends of said cores, the distance between the slots of said yoke being spaced with such relation to the distance between the screws which secure the electro magnets to said strap that said slotted yoke will clamp the magnets in divergent relation with each other when the screws which secure them to the strap are set up. 14. In a polarized ringer magnet, two electro magnets, each having a core which projects at one end of the magnet, said projecting ends being formed with transverse grooves, a yoke having slotted ends which engage the grooves in said cores, means for holding said cores in clamping engagement with said slotted yoke, an armature, an armature supporting bridge and adjustable means for securing said bridge to said yoke, whereby said bridge may be adjusted to vary the distance between the armature and the magnet cores. 15. In a polarized ringer magnet, two electro magnets, each having a core, a strap to which said cores are secured at one end by means which tend to draw the said cores into parallel relation to each other, the other ends of said cores projecting beyond the heads of said magnets and each being formed with a transverse groove, a yoke having slotted ends which engage the grooves in said cores and prevent the cores from being drawn into parallel relation by the said attaching means for the other end of the core, an armature supporting bridge and adjustable means for securing said bridge to said yoke, whereby said bridge may be adjusted to vary the distance between the armature and the magnet cores, and an armature pivoted to said bridge. 16. In a polarized ringer magnet, two electro magnets each having a core, a support to which said cores are secured at one end by means which tend to draw the said cores into parallel relation to each other, the other ends of said cores projecting beyond the ends of said magnets and each being formed with a transverse groove, a yoke having slotted ends which engage the grooves in said cores and prevent the cores from being drawn into parallel relation by the said attaching means for the other ends of the cores, an armature and an armature support connected with said yoke. In testimony whereof I affix my signature, in presence of two witnesses.
